UNITED STATES PATENT OFFICE.

WILLIAM L. DENCH, OF PELHAM, NEW YORK, ASSIGNOR TO ELLIOTT-FISHER COMPANY, OF NEW YORK, N. Y., A CORPORATION OF DELAWARE.

NUMBER-WHEEL LOCK FOR CALCULATING-MACHINES.

942,487.

Specification of Letters Patent. Patented Dec. 7, 1909.

Application filed March 8, 1908. Serial No. 418,978.

To all whom it may concern:

Be it known that I, WILLIAM L. DENCH, a citizen of the United States, residing at Pelham, in the county of Westchester and State of New York, have invented certain new and useful Improvements in Number-Wheel Locks for Calculating-Machines, of which the following is a specification.

This invention relates to an improvement 10 in calculating machines of that type which includes a series of number wheels and a master wheel which is movable laterally to engage the number wheels in succession.

The particular machine with reference to 15 which the present embodiment of the invention is primarily designed is what is known as the Elliott-Fisher combined billing and adding machine, which includes in its organization a flat platen typewriter on the 20 frame of which is mounted a totalizer or register including a series of number wheels, and on the carriage of which is mounted a master wheel, laterally movable into coöperative relation with successive number 25 wheels as the carriage advances, and rotated different distances by the operation of the numeral keys of the typewriter through what are known as differential connections. This arrangement results in the addition of 30 a series of numbers as they are printed in a column by the typewriter.

The object of the invention is to prevent the simultaneous operation of two number wheels in the event that a key is struck 35 while the master wheel occupies an intermediate position in its movement from one number wheel to the next. To the accomplishment of this object the machine is equipped with a number wheel lock movable 40 laterally with the master actuator to engage and lock successive number wheels. The lock is located in advance of the master wheel and remains in locking engagement with the number wheel toward which the 45 actuator is moving, until said actuator has fully cleared the preceding number wheel.

In the accompanying drawings—Figure 1 is a vertical sectional view of so much of an Elliott-Fisher billing and adding machine 50 as is necessary to illustrate the application of my invention thereto. Fig. 2 is a plan view of certain elements of the machine, the differential operating mechanism for the master wheel being omitted, and the front 55 portion of the register being in section to

show the general relation of the master wheel, the number wheels, and the number wheel lock. Fig. 3 is a detail view showing the relation of the number wheels, master wheel and number wheel lock when the 60 master wheel occupies an intermediate position in its travel from one number wheel to the next, and Fig. 4 is a detail view of the number wheel lock detached.

A comprehensive understanding of the invention will be facilitated by a somewhat further description of the machine to which it is shown applied.

The Elliott-Fisher billing machine is what is known to commerce as a flat platen typewriter. A flat platen 1 is equipped with tracks 2 upon which travels longitudinally for line spacing, the machine frame 3. Mounted to travel on the frame 3, in a lateral direction with respect to the platen, for 70 letter spacing, is a carriage 4 equipped with printing mechanism in the form of type-bars 5 operated through suitable intermediate connections from keys 6. The machine is equipped with both letter and numeral type 75 and keys therefor, but in the accompanying drawing the upper or rearmost bank of keys only is indicated, since these are the numeral keys and are the only ones concerned with the adding machine of which my present improvement is an adjunct.

In rear of the frame 3 upon suitable brackets is a register supporting bar 7 on which is adjustably carried a register 8 which includes, as usual, a series of denominational members 90 9 in the form of peripherally toothed wheels. These wheels are also known as number wheels, since they either have numbers displayed thereon or communicate motion to registering wheels equipped with numbers 95 exhibited at a sight opening in the register casing. The register shown is of the latter type.

The number wheels 9 are adapted to be operated by a master wheel or actuator 10 100 mounted on the carriage 4 and movable therewith to engage successive number wheels as the carriage advances to present the printing point of the typewriter opposite the different denominational positions of a column 105 of numbers being printed on the work sheet. The master wheel 10 is rotated a different distance, to-wit from one to nine increments, by the several numeral keys of the typewriter through suitable intermediate differ- 110

ential connections indicated generally as 11. The entire organization as thus far described is well known in the art and it need only be remarked that when a numeral key of the typewriter is operated to print a digit in a given denominational position, the master wheel 10 will be simultaneously rotated to operate the number wheel of corresponding denominational position, a number of increments corresponding to the value of the digit printed. Thus if the digit 5 is printed in the hundreds order of the column on the work sheet, the hundreds wheel of the register will be rotated five-increments or units of movement.

In combined typewriters and adders the distance from one denominational position to the next is comparatively restricted because the average spacing of a typewriter is 20 ten to the inch. Necessarily, therefore, the number wheels of the register are closely spaced. As a result of this the master wheel when moving laterally from one number wheel to the next engages two number wheels 25 simultaneously at an intermediate point in its movement, that is to say, while it is in the act of moving out of engagement with one wheel and into engagement with the next. It sometimes happens that a key of 30 the typewriter is depressed before the spacing movement of the carriage has completely withdrawn the master wheel from the number wheel just operated, in which event a false operation of one of the number wheels 35 results. To prevent the operation of the number wheels under these conditions, I provide what may be termed a number wheel lock 12 mounted on the carriage 4 close to the right hand side of the master wheel 10 40 and having its rear extremity 13 extended between two adjacent teeth of the number wheel to the right of the one engaged by the master wheel, see Figs. 1 and 2. Preferably the end 13 of the lock 12 is disposed close to 45 the subjacent tooth of the wheel engaged by it in order to prevent any appreciable movement of such wheel. It is sufficient, however, that the lock be so located as to prevent any effective movement of the wheel, 50 to-wit one or more increments or units of movement, as less than this would not effect a false registration.

By reference to Fig. 2, it will be seen that when the master wheel 10 is in full engagement with one of the number wheels 9, the lock 12 will be in full engagement with the next number wheel to the right. If now the number wheel engaged by the master wheel is operated and the carriage released 55 upon the complete depression of the key in the usual manner, the carriage will move toward the right and the master wheel 10 will advance laterally into engagement with the number wheel of next lower order. As 60 the number wheel lock 12 is also mounted

on the carriage, it moves laterally with the master wheel so that, as said master wheel moves into engagement with a number wheel, the lock is moving out of engagement with such wheel. The parts are so related, 70 however, that the number wheel lock does not release the number wheel which it is leaving until the master wheel has moved entirely out of engagement with the next number wheel to the left or the one of next 75 higher order, see Fig. 3. It follows therefore that as long as the number wheel is in engagement with two number wheels, one of the number wheels is held against effective movement by the number wheel lock 80 and therefore neither of such number wheels can be operated.

Whether a number wheel may be operated the instant the master wheel moves out of engagement with the next number wheel to 85 the left, or whether it is locked against operation until the master wheel is in full engagement with it is a matter of choice which depends merely upon the relative positions of the master wheel and the lock 12. It is 90 conducive to high speed of operation to permit one number wheel to commence its operation the instant all danger of the simultaneous operation of two number wheels is 95 passed. I have therefore shown the number wheel lock so spaced from the master wheel that the lock will release a number wheel the instant the master wheel has moved completely out of engagement with the next number wheel to the left. Obviously, however, the lock may be located immediately 100 adjacent to the master wheel so that a number wheel will not be released until the full spacing movement of the carriage has been completed.

The particular form of the number wheel lock or the manner of mounting the same on the carriage is not material, the only requisites being sufficient rigidity of the lock to properly perform its function and movement of the lock with the carriage to advance it across the series of number wheels. In the accompanying drawings the lock is in the form of a narrow metal bar the body portion of which is in angular relation to the lower wheel engaging end 13 and to the upper horizontally disposed end or shank 14, which latter is screwed to one of the brackets 15 which support the register operating connections. To lend rigidity to the 110 bar, a headed screw 16 is passed therethrough midway of its ends and is screwed into the supporting bracket.

It is thought that from the foregoing, the construction and operation of my register 115 wheel lock will be fully understood, but I wish to expressly reserve the right to effect such variations of the illustrated structure as may come fairly within the scope of the protection prayed.

What I claim is:—

1. In a combined typewriting and adding machine, the combination with a typewriter including a carriage, frame, and printing mechanism, of a register having a series of denominational members, a master actuator operated by the printing mechanism of the typewriter, said master actuator being movable to engage successive denominational members and adapted during such movement to engage two members at the same time, and locking means movable with the master actuator to engage and prevent effective operation of a denominational member while the actuator is moving into engagement therewith and before said actuator has cleared the adjacent member.
- 15 2. In a combined typewriting and adding machine, the combination with a typewriter

including a carriage, a frame and printing mechanism, of a register mounted on the frame and having a series of denominational members, a master actuator movable with the carriage to engage successive members and operated by the printing mechanism of the typewriter, and locking means mounted on and movable with the carriage to engage and prevent effective operation of a denominational member while the actuator is moving into engagement therewith and before said actuator has cleared the adjacent member.

In testimony whereof I affix my signature in presence of two witnesses.

WILLIAM L. DENCH.
